[57] CLAIM

The ornamental design for a combined pager and magnetic key, as shown and described.

DESCRIPTION

FIG. 1 is a top, front and left side perspective view of a combined pager and magnetic key showing our new design;

FIG. 2 is a right side elevational view thereof;

FIG. 3 is a bottom plan view thereof;

FIG. 4 is a rear elevational view thereof;
FIG. 5 is a top, front and left side perspective view of a second embodiment of the combined pager and magnetic key illustrated in FIG. 1;

FIG. 6 is a right side elevational view of the embodiment disclosed in FIG. 5;

FIG. 7 is a bottom plan view of the embodiment disclosed in FIG. 5; and

FIG. 8 is a front elevational view of the embodiment disclosed in FIG. 5.

FIG. 1.

FIG. 2.

FIG. 3.

FIG. 4.

FIG. 5.

FIG. 6.

FIG. 7.

FIG. 8.
